CLAIM

The ornamental design for stylus pen, as shown and described.

DESCRIPTION

1. Stylus pen

1.1 : Perspective

1.2 : Front

1.3 : Back

1.4 : Left

1.5 : Right

1.6 : Top

1.7 : Bottom

1.8 : Perspective

1.9 : Enlarged

1.10 : Enlarged view of representation 1.6

1.11 : Enlarged view of representation 1.7

1. Purpose of this design product: the present design product is used for writing or drawing on capacitive screens. 2.

Design point of this design product: the shape of the design.

3.The dot-dash broken lines in the drawings are included for the purpose of depicting the partial enlarged view.
